UNITED STATES PATENT OFFICE.

SMITH HARRIS, OF SOUTH SHAFTSBURY, VERMONT.

SALT AND PEPPER SHAKER.

1,388,036.

Specification of Letters Patent. Patented Aug. 16, 1921.

Application filed February 26, 1921. Serial No. 447,915.

To all whom it may concern:

Be it known that I, SMITH HARRIS, a citizen of the United States, residing at South Shaftsbury, in the county of Bennington and State of Vermont, have invented new and useful Improvements in Salt and Pepper Shakers, of which the following is a specification.

My present invention pertains to salt and 10 pepper shakers of the two compartment type; and it consists in the simple, inexpensive and durable salt and pepper shaker hereinafter described and definitely claimed.

In the accompanying drawings, forming 15 part hereof:—

Figure 1 is a vertical diametrical section of my novel salt and pepper shaker.

Figs. 2 and 3 are top plan views of the 20 device with the uppermost disk in different positions.

Fig. 4 is a detail view illustrative of the manner in which the uppermost foraminous disk and the foraminous disk below it are connected together.

Fig. 5 is a detail view showing the manner in which the lower foraminous disk is 25 connected to the clip for holding the cover of the device against casual displacement from the top thereof.

Similar numerals of reference designate 30 corresponding parts in all of the views of the drawings.

The body 1 of my novel device is preferably formed in one piece of glass though 35 it may be formed of any other material and may be either transparent or opaque in the discretion of the manufacturer. The said body includes a diametrical partition 2 by which it is divided into compartments 3 and 40 4, one compartment being designed to contain salt and the other compartment to contain pepper. At a point adjacent to its upper end the partition 2 is provided at its opposite sides with swells 5. The cover of 45 my novel device is preferably formed of thin sheet metal and includes a lower disk 6 and an upper disk 7^a. The lower disk 6 is provided with a pendent marginal flange 7 to receive the upper end of the body 1.

Said disk 6 is also provided with a slightly 50 raised circular central portion 8 in which and at opposite sides of a diametrical line are formed two groups of apertures 9 and 10; the apertures 9 being comparatively 55 small for the proper discharge of pepper, and the apertures 10 being suitable for the

discharge of salt. Struck from the disk 6 are tongues 11 through the medium of which a channeled member 12 is strongly connected with the disk 6 without the assistance of solder or the like. The channeled member 12 is arranged diametrically at the underside of the disk 6 and is provided with two groups of members 13 shaped to straddle the upper end of the partition 2 and to spring into and out of engagement with the swells 5. Manifestly the clips 13 in coöperation with the swells 5 are adapted to hold the cover against casual displacement from the body 1. When, however, stress is applied to the disk 6 the cover may be quickly and easily pulled off of the body 1.

The upper disk 7^a is provided with a marginal flange 7^b adapted to surround the raised central portion of the disk 6 and to bear on the marginal portion of said disk 6 so as to add to the finished appearance of the cover. Said disk 7^a is provided with two groups of apertures 9^a and 10^a, and is also provided with a finger piece 20 and with one or more pointers 21, the said pointers 21 being adapted to coöperate with signs such as the letters P and S provided on the marginal portion of the disk 6 in order to indicate when the disk 7^a is positioned for the discharge of pepper and when it is positioned for the discharge of salt, it being understood in this connection that when the pepper apertures are opened the salt apertures will be closed and vice versa. In this central portion the disk 7^a is provided with a rectangular aperture 25, and extending over the end walls of the said aperture 25 are tongues 26 struck from the disk 6. The said tongues 26 are narrower than the rectangular aperture 25, and while they serve to strongly hold the disk 7^a down against the disk 6 they are adapted to permit of sufficient movement of the disk 7^a about its center for the opening of the pepper apertures and the closing of the salt apertures and the opening of the salt apertures and the attendant closing of the pepper apertures.

It will be apparent from the foregoing that by observing the sign that is exposed, the user of my novel device is apprised when the disk 7^a is set for the discharge of pepper and when it is set for the discharge of salt, and therefore it is not essential for the body 1 to be made of transparent material. It will

also be apparent that my novel device is susceptible of being cheaply produced inasmuch as the disks 6 and 7^a of the cover are connected together of themselves without the assistance of extraneous means, and the disk 6 is connected by its tongues 11 with the resilient partition-straddling coupler which as hereinafter stated is preferably of channel form and is provided with the two 10 clips 13.

It will further be appreciated from the foregoing that while there is no liability of the cover being casually displaced from the body 1, the said cover may be expeditiously 15 and easily removed when it is desired to replenish the supply of pepper and salt in the body and may as readily be replaced on and secured to the body.

While I describe the member 12 as connected with the disk 6 without the assistance of solder I would have it understood that when deemed desirable solder may be employed. I would also have it understood that the word "signs" as herein employed 25 is intended to comprehend words such as

"Salt" and "Pepper," and when such words are employed the disk 7^a will be allowed sufficient movement to cover the one and uncover the other and vice versa.

Having described my invention, what I 30 claim and desire to secure by Letters-Patent, is:—

A salt and pepper shaker comprising a body having a partition whereby it is divided into compartments and also having 35 swells on the sides of the said partition adjacent to the upper end thereof, in combination with a cover adapted to rest on the body and having at its underside a coupler constructed and arranged to straddle 40 the upper end of the body partition and to be sprung into and out of engagement with the swells thereof; the said coupler being of channel form in cross section and provided with resilient clips, and being connected in 45 diametrical position to the underside of the cover by tongues struck from a portion of the cover.

In testimony whereof I affix my signature.
SMITH HARRIS.
